UNITED STATES PATENT OFFICE.

IRA SCOTT, OF FORT COLLINS, COLORADO.

SWIMMING APPARATUS.

1,081,877.

Specification of Letters Patent. Patented July 9, 1912.

Application filed April 1, 1912. Serial No. 687,721.

To all whom it may concern:

Be it known that I, IRA SCOTT, a citizen of the United States, residing at Fort Collins, in the county of Larimer and State of Colorado, have invented certain new and useful Improvements in Swimming Apparatus; and I do declare the following to be a full, clear, and exact description of the invention, such as will enable others skilled in the art to which it appertains to make and use the same.

This invention relates to improvements in swimming apparatus.

One object of the invention is to provide a swimming apparatus having an improved construction and arrangement of floats whereby the swimmer is supported in a comfortable position.

Another object is to provide an improved propelling mechanism operated by the feet of the swimmer to rapidly propel the apparatus with comparatively little effort and which is provided with an improved means for steering the same in the desired direction.

With these and other objects in view the invention consists of certain novel features of construction, and the combination and arrangement of parts as will be more fully described and claimed.

In the accompanying drawings; Figure 1 is a side view of my improved swimming apparatus; Fig. 2 is a top plan view thereof; Fig. 3 is a rear end view; Fig. 4 is a cross sectional view on the line 4-4 of Fig. 2; Fig. 5 is a similar view on the line 5-5 of Fig. 2; Fig. 6 is a vertical cross sectional view on the line 6-6 of Fig. 1.

My improved swimming apparatus comprises a front body supporting float 1, which may be of any suitable construction, but which is here shown and preferably consists of a hollow body of substantially semi-elliptical form in cross section and of sufficient length to receive the trunk or body of the swimmer. The upper side of the float 1 is depressed to form a cradle-like receptacle 2 into which the swimmer lies, preferably in a face down position. The float 1 has its rear end secured to a bifurcated frame attaching member 3 to which is bolted or otherwise firmly secured the forward end of a gear and propeller supporting member 4 in which midway of its ends is arranged an open frame 5. On the rear end of the

frame 5 is arranged a tubular shaft bearing or supporting section 6.

Revolutely mounted in the frame 5 is a crank shaft 6' the ends of which project beyond the opposite sides of the frame and have arranged thereon cranks 7 with which are pivotally connected pedals 8. On the crank shaft 6' is fixedly mounted a beveled propeller operating gear 9 with which is engaged a beveled gear pinion 10 fixed on the forward end of a propeller operating shaft 12. The rear end of the shaft 12 projects a suitable distance beyond the shaft supporting tube 6 and has fixed thereon a suitable propeller 13.

Secured to the shaft supporting tube 6 by means of the clamping bracket 14 is a rear float 15 which may be of any suitable construction but which is here shown and is preferably in the form of a hollow body of elliptical shape in cross section and having its forward end tapered to a point as shown.

Secured to the lower side of the tubular shaft supporting member 6 and extending rearwardly therefrom is a lower rudder 80 supporting bracket 16, while to the rear portion of the float 15 is secured a right angularly formed upper rudder supporting bracket 17. Revolutely mounted in the brackets 16 and 17 is a vertically disposed rudder shaft 18 on which between said brackets and projecting a suitable distance in the rear of the same is a rudder blade 19. Fixedly mounted on the upper end of the rudder shaft 18 is a cross head or tiller bar 90 20 to the ends of which are connected the rear end of a tiller or rudder operating cord 21 which extends forwardly through suitable guides 22 on the brackets 14 and 17 of the float 15 and through guide eyes 23 on the upper edges of the forward end of the float 1 and across said forward end of the float as shown in Fig. 2 of the drawings. Secured to the portion of the cord 21 which crosses the float 2 is a handle or grip 100 24 by means of which either end of the cord may be pulled to turn the rudder in the desired direction as will be readily understood.

In the operation of the apparatus the swimmer lies in the recess 2 of the float 1 in the manner described, with the feet engaging the pedals 8 of the crank shaft 6' whereupon when said shaft is operated by the movement of the pedals the move-

ment of the shaft is transmitted to the propeller shaft and propeller through the gears 9 and 10 as described. The propeller when thus operated will drive the apparatus and the swimmer along much faster than the swimmer could propel himself in the ordinary manner of swimming and with a much less effort.

10 My improved swimming apparatus may be used not only as a pleasure device in swimming and bathing, but may also be employed as a life saving apparatus for rapidly reaching and rescuing persons in danger of drowning.

15 From the foregoing description taken in connection with the accompanying drawings, the construction and operation of the invention will be readily understood without requiring a more extended explanation.

20 Various changes in the form, proportion and the minor details of construction may be resorted to without departing from the principle or sacrificing any of the advantages of the invention as shown.

25 Having thus described my invention, what I claim is:

A swimming apparatus comprising a body supporting float, a bifurcated frame attaching member secured to the rear end 30 of said float, a gear frame and shaft bear-

ing member secured to said frame attaching member, a crank shaft revolvably mounted in said frame member, operating pedals arranged on said shaft, a propeller shaft revolvably mounted in said shaft bearing 35 member and geared to said crank shaft, a propeller fixed on the outer end of said shaft, a hollow float secured to said frame and bearing member and spaced a suitable distance above the same, a lower rudder 40 supporting bracket and an upper rudder supporting bracket secured respectively to said bearing and frame member and to said float, a rudder shaft revolvably mounted in said brackets, a rudder fixed on said shaft, 45 a tiller bar fixed on the upper end of said rudder shaft, a tiller cord connected to the ends of said tiller bar, and extending forwardly and across the forward end of said body supporting float, and a handle secured to said cord whereby the same may be operated to turn the rudder in the desired direction for steering the apparatus.

In testimony whereof I have hereunto set my hand in presence of two subscribing 55 witnesses.

IRA SCOTT.
